STEP BUMPER

William Renouf, Kenilworth, Ill., assignor to Nash Bros.
Co., Evanston, Ill., a corporation of Delaware

Filed Feb. 23, 1967, Ser. No. 5,916

Term of patent 14 years

(Cl. D14—6)

FIG. 1

FIG. 2

FIG. 3

FIG. 4

FIG. 1 is a perspective view of the step bumper design;

FIG. 2 is a top plan view of the step bumper;

FIG. 3 is a rear elevational view;

FIG. 4 is an enlarged side elevational view.

The portions shown in broken lines in FIGURE 1 are included for illustrative purposes only. The characteristic feature of my design resides in the arrangement of the parallel, horizontally disposed depressions wherein same extend from the forward ends of the step bumper and terminate to either side of the step recess.

I claim:

The ornamental design for a step bumper, substantially as shown and described.
